[57] CLAIM

The ornamental design for an archery sight, as shown and described.

DESCRIPTION

FIG. 1 is a perspective view of an archery sight showing my new design, the broken lines being shown for illustrative purposes only;

FIG. 2 is a front view thereof;

FIG. 3 is a back view thereof;

FIG. 4 is a top view thereof;

FIG. 5 is a side view thereof taken from the right of FIG. 2;

FIG. 6 is a side view thereof taken from the left of FIG. 2;

FIG. 7 is a bottom view thereof.
